Q. BARBOSA

SWIMMING DEVICE

Filed Sept. 30, 1927

INVENTOR

BY

QUINTINO BARBOSA.
Richard D. Owen,
ATTORNEY

UNITED STATES PATENT OFFICE.

QUINTINO BARBOSA, OF BRIGHTON BEACH, NEW YORK, ASSIGNOR OF ONE-HALF TO
CHARLES ALTMAN, OF BROOKLYN, NEW YORK.

SWIMMING DEVICE.

Application filed September 30, 1927. Serial No. 223,132.

This invention relates to swimming devices and in particular to a type adapted to be placed upon the feet of the swimmer to assist in propelling him through the water.

5 A particular object of the invention is to provide a swimming device which may be quickly accommodated to the feet of the wearer and which will materially aid in its propulsion, the device being provided with 10 blades whereby their movement through the water in an anti-swimming direction will offer least resistance due to the foldability thereof.

A still further object of the invention is 15 to provide a swimming vein or blade which will fold up when drawn in one direction through the water and which will maintain its open position to resist movement through the water when forced in the opposite direction whereby the swimmer is enabled to 20 advance rapidly through the water by a rearward kicking of the feet.

A still further object of the invention is 25 to provide a device of this character which can be detachably secured to the feet of the swimmer and which may be incorporated in a complete shoe or may be made for use as part of a sandal to fit closely about the feet of the swimmer.

30 To enable others skilled in the art to fully comprehend the underlying features of my invention, that they may embody the same in the various modifications in structure and relation contemplated, a drawing depicting a 35 preferred form has been annexed as a part of this disclosure and in such drawing, similar reference characters denote corresponding parts throughout all the views, of which,

Figure 1 is a view in perspective showing 40 my improved swimming device as applied to a shoe.

Figure 2 is a sectional view taken on the line 2—2 of Figure 1 and shows the method 45 of attaching the swimming blade to the side of the shoe.

Figure 3 is a view in perspective of a modified form showing the use of my swimming blade in connection with the sandal, which is adapted to fit closely about the foot of 50 the swimmer.

Figure 4 is a sectional view taken on the line 4—4 of Figure 3 and shows the method 55 of securing the swimming blade to the side of the sandal.

Figure 5 is a sectional view taken on the

line 5—5 of Figure 3 and shows the method of connecting the front portion of the blade with the toe encircling strap of the sandal.

Referring to the drawings in detail, 5 indicates a shoe of the swimming variety which is usually made up of water-resistant material, closed at the front as by the laces 6 and provided with the extended ankle encompassing portion 7. The inner side of the shoe, and it will be understood that my swimming device is applicable to the right and left foot shoes, description of one of which will suffice, and the shoe, on its interior wall is provided with a reinforcing element 8, at the ankle portion thereof and also with a 10 reinforcing element 9 in the toe portion thereof. In order to securely hold in suitable position on the ankle and toe portions of the shoe, the outer steel hinge members 10 and 11 respectively, it of course being understood 15 that the hinge 10 is secured through the medium of suitable rivets 12 to the inner reinforcing member 8 and the hinge member 11 is secured in the same manner to the inner reinforcing member 9. The hinge members 20 10 and 11 have pivotal connection with other hinge members 13 and 14 which are secured to a blade 15. A suitable block 16 is positioned on the hinge plate 13 and has secured thereto, as at 17, one end of a coil spring 18, 25 the other end of which is attached to the upper edge of the hinge plate 10. The block 16 prevents movement of the blade 15 above a horizontal plane against the action of the spring 18, it being readily understood that 30 when the foot is dragged through the water by the doubling up of the leg that the resistance of the water against the blade 15 will overcome the tension of the spring and allow 35 the blade to assume an angular position from the horizontal wherein it will not resist passage through the water, but when a kicking 40 movement is given to the leg, the resistance of the water against the under side of the blade 15 will cause it to assume a horizontal 45 position in which position it will be held by the blocks 16 bearing against the hinge plate 50 10. 100

It is quite evident in this form of construction that the shoe, being tightly laced upon the leg and foot of the swimmer, will permit 105 efficient operation of the blade in its movements through the water in one direction, allowing the blade to fold up so as to offer little resistance to the bending of the leg prepara- 110

tory to a kicking movement and when the kicking movement is started, the blade will open offering resistance to its passage through the water and consequently aiding 5 the swimmer in his swimming movement.

Referring to the modification shown in Figures 3, 4 and 5, it will be noted that instead of the shoe, I have provided a sandal member 19, consisting of the upper strap portion 20 and lower strap portion 21, joined by the ankle strap 22, to which is secured, as by riveting or other suitable media, the reinforce band 23, this band extending around and underneath the heel and providing a solid member to which may be riveted or otherwise secured, the hinge plate 24. This hinge plate has soldered thereto, a hood 25, which covers the coil spring 26, the spring itself being secured at its lower end to the hinge plate 27 which is secured to the blade 28 in the same manner hereinbefore described, the bottom of the hood 25 lies adjacent the hinge plate 27 and consequently prevents upward movement of the blade 28 from its position in a horizontal plane, thus permitting a swimming movement of the foot to cause the blade 28 to remain in its horizontal position to offer resistance to the water and enable the swimmer to advance more rapidly therethrough. The sandal is further provided with the sole strap 29 and instep strap 30 which are joined at their front ends by the toe strap 31 to which is also secured, a hinge plate 32, which pivotally holds the hinge plate 33, which, in turn, is secured, as before described to the blade 28. It is quite evident, that when the sandal is placed upon the foot and buckled by the buckles provided therein for that purpose, that it will act in the same manner and perform the same function as the swimming blade, described in Figures 1 and 2. It is quite evident, therefore, that I have provided a swimming device which will materially aid the swimmer in his advance through the water.

It is of course understood that various materials may be used in the construction of my device but preferably I employ wood for use in connection with the blade and a 50 rust-resisting metal for use in connection

with the hinges and the hood, the spring, of course, being made out of brass or other non-corrodible metal which is not affected by salt or fresh water. The brace, of course, is made of heavy spring steel and provides the support 55 necessary between the blade and the foot whereby the blade will operate efficiently and be a useful adjunct in swimming.

It is evident, therefore, that I have provided a swimming device which may be employed in connection with both feet and which will not only not interfere with the action of the swimmer in the water but will materially aid in his progress therethrough.

It is also evident, that I have provided a swimming device of light material which may be readily attached to the feet of the swimmer and which will not interfere with his walking on the shores preparatory to entering the water.

It is also evident, that I have provided a device which may be used in connection with either sandals or shoes and which may be quickly and securely attached to the feet of the wearer and one which can be produced at 75 small cost with a resulting saving to the user.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claim. 80

Having thus described my invention, what I claim as new and desire to secure by United States Letters Patent is:—

A swimming device of the character described comprising a sandal for attachment 90 to the foot, rigid members secured to the sandal, a plate hinged to said rigid members, a spring for normally urging the plate to extended position, a hood secured to one of the rigid members and forming a housing for 95 said spring and the lower edge of the hood arranged to limit the pivotal movement of the plate in one direction.

In testimony whereof I affix my signature.
QUINTINO BARBOSA. [L. S.]
